United States Patent

Des. 239,851
Patented May 11, 1976

239,851

WATER SCOOTER

Jack R. Bedient, 55 Richardson Drive,
Henderson, Nev. 89015

Filed Nov. 3, 1972, Ser. No. 303,446

Term of patent 14 years

Int. Cl. D12—14; D21—02
U.S. Cl. D34—42

FIG. 1

FIG. 2

FIG. 3

FIG. 4

FIG. 1 is a top plan view of a water scooter showing my new design;

FIG. 2 is a side elevational view thereof;

FIG. 3 is a bottom plan view thereof; and

FIG. 4 is a sectional view taken about line 4—4 of FIG. 2.

The rope shown fragmentarily in FIGS. 1, 2 and 3 is so shown to indicate indeterminate length.

I claim:

The ornamental design for a water scooter, as shown and described.
